UNITED STATES PATENT OFFICE.

WALTER TITTLE, OF PHILADELPHIA, PENNSYLVANIA, ASSIGNOR, BY MESNE ASSIGNMENTS, TO ROBERT M. ZEARING, JR., OF PHILADELPHIA, PENNSYLVANIA.

DISPENSING DEVICE.

Application filed May 21, 1925. Serial No. 31,895.

This invention relates to brushes of the type which include in their structure a container for the soap or other material, in a plastic or semi-liquid state, which the brush 5 is intended to apply, and the principal object of the invention is to provide a simple strong and commercially practical brush of this type including a hollow handle adapted to receive a container for the material with 10 which the brush is intended for use.

Another object of the invention is to provide in novel and practical form a container in the nature of a refill or cartridge adapted for use with a brush of this type and including in itself all the elements necessary 15 to expel the contained material.

A further object of the invention is to provide a container of the specified type having novel and improved mechanism for expelling 20 the contained material.

The invention further contemplates the provision of a container having novel means for positively sealing the discharge port during the periods in which the device is 25 not in use.

The invention also contemplates certain novel and advantageous details of construction as hereinafter fully described and as 30 illustrated in the attached drawings, in which:

Figure 1 is a view in perspective of the hollow body or handle of the brush;

Fig. 2 is a view in perspective of the ferrule which holds the bristles and which is 35 adapted to be attached to one end of the body illustrated in Fig. 1;

Fig. 3 is a view in perspective of the bottom retaining element adaptable to one end of the brush casing;

Fig. 4 is a view in perspective of the container which is adapted to fit within the brush casing shown in Fig. 1 and to be retained thereby by the ring shown in Fig. 3;

Fig. 5 is an enlarged vertical section of 40 the assembled brush;

Fig. 6 is a perspective view of the stem-locking member secured to the bottom of the container;

Fig. 7 is a perspective view of the lower 50 end of the threaded stem of the container with the actuating element attached thereto, which cooperates with the locking element

shown in Fig. 6 to secure the stem in the port-closing position;

Fig. 8 is a view in perspective of the 55 plunger confined within the container;

Fig. 9 is a view in perspective of the plunger sleeve;

Fig. 10 is an enlarged vertical section illustrating the details of the plunger sleeve 60 shown in Fig. 9;

Fig. 11 is a view in perspective of the valve cap, and

Fig. 12 is an enlarged vertical section of the upper end of the threaded stem with the 65 valve cap attached and the rubber valve carried by the said cap.

With reference to the drawings, in which for the purpose of illustration I have shown an embodiment of my invention in the form 70 of a shaving brush, the device may comprise a hollow substantially tubular body portion 1 and a ferrule 2 holding the usual bristles 3. As clearly illustrated, the upper end of the body 1 is slightly tapered as also is the ferrule 2 which is adapted to fit snugly over 75 the correspondingly tapered end of the body and to be retained thereon by the frictional contact between these parts.

The brush further comprises as a part of 80 the casing or housing a tapered retaining ring 4 which fits over a correspondingly tapered lower end of the body 1 and functions to retain, in an operable position, a 85 container 5, such as shown in Fig. 4, which is adapted to be inserted within the body 1. As with the ferrule 2, the frictional engagement of the tapered parts of the retaining ring 4 and the body 1 are relied upon to hold the said ring on the body. While the 90 above described tapered formations are desirable by reason of their extreme simplicity and efficiency, it is clear that other retaining means for the ferrule and for the bottom ring may be employed.

For reasons hereinafter made clear, it is necessary that the container 5 be prevented from rotational movement in the casing 1, and for this purpose I provide at the top of the casing a polygonal or other irregularly shaped projection 6 formed in the present instance as an integral part of the body 1, and at the upper end of the container 5 I provide a correspondingly shaped exten- 95 100

sion 7 which fits within the part 6 of the casing. The container 5 further comprises above the part 7 a nozzle portion 8 which is provided with a discharge port 9 at its upper 5 end and is adapted to project upwardly through the base of the bristles, as clearly illustrated in Fig. 5, when the parts are assembled. Projecting from the bottom of the container 5 is an operating member 10 by 10 means of which, as hereinafter described, any desired portion of the contents of the container may be expelled into the body of the bristles, and the ring member 4 is so shaped as to provide free access to this actuating member while retaining the container 5 15 in the casing 1.

Referring to Figs. 5 to 12, inclusive, the container 5 comprises a cylindrical shell 11 having at the top a cap 12 which includes 20 the part 7 and the nozzle 8. In the bottom of the casing is secured a locking member 13 which projects downwardly below the container and which comprises, as best shown in Fig. 6, transversely extending and oppositely 25 inclined wings 14, 14. The member 13 is longitudinally apertured for reception of the lower end of a threaded stem 15 axially aligned with, and lying within, the interior of the shell 11, said stem having secured to 30 the end thereof which projects beyond the member 13 the operating member 10, best shown in Fig. 7, which constitutes a means for rotating the stem and which is also adapted to cooperate with the inclined wings 35 14, 14, of the member 13, as hereinafter more fully described, to lock the stem 15 in such a position as to cause the discharge port 9 of the nozzle 8 to be closed thereby.

For the purpose of insuring a complete 40 closure of the port 9, the stem 15 is provided at its top with a valve plate or cap 16 best shown in Fig. 11 which is adapted to retain thereon a rubber or other suitable valve member 17. The cap 16 is in the form of a 45 flat plate having ears 18 punched out of the plate and turned over so as to grip the sides of the rubber valve element 17, as shown in Fig. 12.

The member 10 which is substantially in 50 the form of a hollow cylinder is provided with a diametrical slot or opening 19 of sufficient width to permit the passage into its interior of the wing members 14 of the part 55 13. When therefore the member 10 with the stem is forced inwardly of the shell 11 to the position shown in Fig. 5 so that the member 13 enters through the opening 19, the valve 60 17 is brought tightly against the hole 9, and when therefore the actuating member 10 is rotated to the right, see Figs. 6 and 7, it rides up on the inclined wings 14, 14, and thereby still further moves the stem 15 inwardly and brings the valve 17 even more tightly against the port 9, thereby insuring

a tight closure and also locking the stem in 65 this port-closing position.

The container or cartridge also comprises inside of the shell a plunger which in the present instance includes a metal disk 20 to which is attached a rubber or other suitable 70 disk 21, the metal disk 20 in the present instance having, as shown in Fig. 8, pressed out tongues 22 which function to hold the rubber disk against the face of the metal disk. This metal disk is loosely supported 75 upon a sleeve 23 on the stem 15, having threaded engagement with the latter by reason of inward projections 24 at the top and bottom edges which engage the threads of the stem. The sleeve has an outwardly ex- 80 tending flange 25 at one end and is turned over as shown at 26 at the other end to prevent the plunger from passing off the sleeve while permitting the plunger and the sleeve a certain axial relative movement. To prevent 85 relative rotational movement of the plunger and the sleeve, the latter is provided with a longitudinal ridge or tongue 27 which fits into a corresponding recess 28 in the centre bore of the metal disk 20.

With the aforescribed construction, operation of the device is as follows:

Assuming that the stem 15 is in the advanced or port-closing position as previously described and as shown in Fig. 5, a partial 95 turn of the element 10 to the left brings the wings 14 of the locking element 13 into registry with the opening 19 in the member 10 and permits the latter member with the stem 15 to be drawn downwardly until 100 pressed-out tongues 30 thereon engage the inner end of the locking element 13. This uncovers the port 9. It will be noted that axial movement of the stem 15 does not affect the plunger 20-21, since the sleeve 23 is 105 axially slid able with respect to the plunger. With the parts in this position, rotation of the member 10 and the stem 15 to the right effects a movement of the sleeve 23 toward the discharge end of the container until the 110 flange 25 engages the under side of the plunger 20-21, after which a continued rotational movement of the stem 15 advances the plunger and expels the contained material, in the present instance shaving soap in 115 a plastic or semi-liquid state, from the uncovered port 9. When sufficient soap has been expelled, the member 10 with the stem 15 is rotated to the left or in a reverse direction which has the effect of causing the 120 sleeve 23 to be retracted on the stem, the plunger 20-21, however, remaining stationary by reason of the free relative movement between the plunger and the sleeve. After the sleeve has moved until the turned- 125 over flange 26 engages the disk 20 of the plunger and with the member 10 in position in which the wings 14, 14, of the member

13 are again in registry with the opening 19, the member 10 with the stem 15 may be moved inwardly of the container, thereby bringing the valve 17 against the inner side 5 of the port 9. A partial rotation of the member 10 in a right hand direction results in the cooperative action of the inclined wings 14, 14, and the said member 10 to force the stem inwardly so that the valve 10 17 bears against and tightly closes the port 9 and so that the stem is locked in this port-closing position.

A material advantage in this construction resides in the extreme simplicity of the device and the low cost of manufacture. A further material advantage resides in the fact that the mechanism by which the material is expelled from the container or cartridge constitutes a part of the cartridge and is such as to provide for a positive sealing of the container during the periods of time that the brush is not in use.

It will be noted that the retaining ring 4 at the bottom of the casing extends below the end of the container 5, and that the member 10 when in the locked position of the stem lies within the plane of the lower edge of the ring 4 as indicated in Fig. 5, thereby preventing the member 10 from interfering with standing the brush in the upright position illustrated. However, when the port 9 is open, the operating knob 10 extends sufficiently below the base line of the ring 4 to prevent the brush from standing in an upright position, for the purpose of insuring the port 9 being closed before the brush is laid aside after use.

I claim:

1. A container comprising a hollow shell having a discharge port at one end, a plunger movable in the shell, a stem having threaded engagement with the plunger and projecting through one end of the shell, the inner end of said stem constituting a valve for closing the discharge port of the container and the stem being axially movable in the container, and means providing for relative axial movement without turning between the stem and the plunger.

50 2. A container comprising a cylindrical shell having a discharge port at one end, a plunger in said shell, a stem having threaded engagement with the plunger and projecting through one end of the shell, said 55 stem constituting also a valve for closing the discharge port of the container and being axially movable in the container, and cooperating parts on the stem and on the container for locking the stem in the valve-closing position.

3. A container comprising a cylindrical shell having a discharge port at one end, a threaded stem projecting through the opposite end of the shell and adapted to close the said discharge port, said stem being

axially movable in the container, a plunger having threaded engagement with the stem, means permitting axial movement of the stem to close or open the discharge port without disturbing the plunger, and means for locking the stem in the port-closing position. 70

4. A container comprising a cylindrical shell having a discharge port at one end, a threaded stem projecting through the opposite end of the shell and adapted to close said discharge port and being axially movable in the container, a threaded sleeve on said stem, and a plunger splined to the sleeve and adapted for limited free movement axially thereof. 75 80

5. A container comprising a cylindrical shell having a discharge port at one end, a threaded stem projecting through the opposite end of the shell and being axially movable in the container so as to constitute a valve for closing the said discharge port, a threaded sleeve on said stem, a plunger splined to said sleeve and having limited movement axially thereof, and means for locking the stem in port-closing position. 90

6. A container comprising a cylindrical shell having a discharge port at one end, a threaded stem projecting through the opposite end of the shell and being axially movable in the container so as to constitute a valve for closing the said discharge port, a threaded sleeve on said stem, a plunger splined to said sleeve and having limited movement axially thereof, and cooperative elements on the container and stem externally of said container for locking the stem in port-closing position. 95 100

1   7. A container comprising a cylindrical
2   shell having a discharge port at one end, a 105
3   threaded stem projecting through the op-
4   posite end of the shell and being axially
5   movable in the container so as to constitute
6   a valve for closing the said discharge port,
7   a threaded sleeve on said stem, a plunger 110
8   splined to said sleeve and having limited
9   movement axially thereof, and cooperative
10   elements on the shell and on the stem ex-
11   ternally of the container for locking the
12   stem in port-closing position, one of said
13   elements including a surface inclined to the
14   plane of the bottom of the container coop-
15   eratively engaged by the other element. 115

8. A container comprising a hollow shell having a discharge port at one end, a plunger movable in the shell, a stem having threaded engagement with the plunger and projecting through one end of the shell, the inner end of said stem constituting a valve for closing the discharge port of the container and the stem being axially movable in the container, means providing for relative axial movement without turning between the stem and the plunger, an operating member for the stem on the outwardly 120

125

130

projecting end thereof, and an element on the shell adapted to cooperate with said actuating element to force the stem tightly against the ported end of the container and to retain the stem in the port-closing position.

9. A container comprising a cylindrical shell having a discharge port at one end, a plunger in said shell, a stem having threaded engagement with the plunger and projecting through one end of the shell, said stem

constituting also a valve for closing the discharge port of the container and being axially movable in the container, a hollow operating element on the projecting end of said stem, an element on the shell adapted to be embraced by said actuating element whereby the stem is retained in a port-closing position, and means providing for separation of said elements to permit rotation of the stem to advance the plunger in the container.

WALTER TITTLE.
